UNITED STATES PATENT OFFICE.

BLANCHE MARGARITA STRACHAN, OF MONTREAL, QUEBEC, CANADA.

VEIL.

1,263,958.

Specification of Letters Patent. Patented Apr. 23, 1918.

Application filed September 5, 1917. Serial No. 189,888.

To all whom it may concern:

Be it known that I, BLANCHE MARGARITA STRACHAN, (wife of Kenneth D. Strachan,) a subject of the King of Great Britain, and 5 resident of the city of Montreal, Province of Quebec, Dominion of Canada, have invented certain new and useful Improvements in Veils; and I do hereby declare that the following is a full, clear, and ex- 10 act description thereof.

My invention relates to the large and more or less light-weight veils used by ladies to protect their heads and headgear while automobileing or traveling on the water, or otherwise exposed.

Heretofore considerable inconvenience in wearing these large veils has been experienced owing to the fact that after having been carefully and fashionably put on the wearer 20 could not uncover her face without disturbing the veil to such an extent that it has been difficult to prevent it from either falling completely from the head and shoulders or sagging over the face more than might 25 be desired for effect.

My invention has for its object to provide a veil suitable for the use of lady-automobilists and tourists which can be readily fastened in place and without being unfastened, be adapted to either cover the face 30 by hanging loosely over it and over the shoulders and down the back or be drawn beneath the chin and fastened around the neck. To this end the invention consists of 35 a full-fashioned veil of the automobile and tourist type preferably of slightly greater length than width and having a ribbon or other flexible length arranged parallel to one side edge and at a position distant from 40 that side edge less than half the width of the veil, this ribbon or the like being fastened at its middle to the veil and having its ends free, the ribbon itself being of sufficient length to be tied around the head or 45 headgear of the wearer. This side edge of the veil has a pair of ribbons attached thereto and being of sufficient length to be wound in opposite directions around the neck of the wearer and tied either at the back or 50 in front.

For full comprehension, however, of my invention, reference must be had to the accompanying drawings in which similar reference characters indicate the same parts, 55 and wherein:

Figure 1 is a side elevation of a head of

a lady wearing a hat and having my improved veil initially fitted in place;

Fig. 2 is a similar view with the back portion of the veil thrown over the head, the 60 entire veil hanging free;

Fig. 3 is also a similar view with the veil tied to completely inclose and protect the head of the wearer; and

Fig. 4 illustrates the veil removed and in 65 plan view.

My improved veil may be made from any approved veiling material, but I prefer to use very light chiffon or Georgette crêpe and furnish it with a binding 2 of ribbon. 70

The veil is preferably of oblong rectangular form.

In a line approximately two-fifths distance from and parallel to one side edge 20 I form a pair of button-holed openings 3 75 spaced a sufficient distance apart to encircle the front portion only of the hat of the wearer. A ribbon 4 of sufficient length to be tied around the crown of the wearer's hat is stitched to the veil between the openings and its ends 5 are passed through the openings and hang from the opposite side of the veil. This arrangement permits the veil to be tied securely to the hat, as shown in Fig. 1, without any strain upon the veiling material, and so attached that the veil may be thrown to the front or back of the wearer without disturbing the position in which it is initially fitted.

In order to tie the veil about the head of 90 the wearer a pair of ribbons 6 are fastened to the side edge 20 and spaced a distance apart to loosely encircle the front portion only of the neck of the wearer over the veil, the ribbons 6 being tied in a bow either at 95 the front or back of the neck and also over the veil, as shown in Fig. 3.

In putting on my improved veil the wearer takes the ends 5 of ribbon 4 and draws the ribbon, and with it the veil, taut across the 100 front of the crown of her hat and ties the ends at the back as before mentioned (Fig. 1). The veil is in this way fitted in correct position with the edge 20 and the front portion 21 of the veil hanging over the face 105 as shown in dotted lines Fig. 1. The back portion 22, which is longer than the front portion owing to the particular position of ribbon 4 on the veil, will then also hang down the front. This long back portion is 110 then thrown back over the head as shown in Fig. 2. The veil may be worn in this

way if desired, or the front portion 20 may be thrown back and the face uncovered without any danger of the veil being displaced from the position in which it is initially fitted. With the veil in the position shown in dotted lines in Fig. 2 it may be readily fastened to completely inclose and protect the head of the wearer by tying the ribbons 6 at the back of the neck as shown in Fig. 3.

10 It will be seen from the foregoing that my improved veil may be put on before leaving on a trip and may be tied to protect the head as shown in Fig. 3 or may be opened and thrown back and allowed 15 to hang free as shown in Fig. 2 while still fastened to the hat or permitted to hang entirely in front as shown in Fig. 1, as circumstances may require, and again tied to protect the head as in Fig. 3, without being 20 disturbed from its proper position with regard to the face of the wearer; and although I have shown a binding and described a preferred weight of material, the binding may be dispensed with and other 25 materials used without departing from the spirit of my invention. Furthermore, other means of tying the edge of the veil around the neck of the wearer may be used within the scope of my invention.

30 What I claim is as follows:

1. The combination with a veil for automobilists' and tourists' use and being in dimensions of greater length than width and having a pair of spaced openings in a line 35 parallel to one side edge of the veil and

located approximately one-third the distance from that side edge to the opposite side edge, of a ribbon of greater length than the distance between the holes and having its middle portion fastened to the body of the 40 veil between the holes and its ends passed through said holes for the purpose of fastening the body of the veil to the head of the wearer.

2. The combination with a veil for automobilists' and tourists' use and being in dimensions of greater length than width and having a pair of spaced openings in a line parallel to one side edge of the veil and located approximately one-third the distance 45 from that side edge to the opposite side edge, of a ribbon of greater length than the distance between the holes and having its middle portion fastened to the body of the 50 veil between the holes and its ends passed through said holes for the purpose of fastening the body of the veil to the head of the wearer; a pair of ribbons each of greater 55 length than the size of the neck of the average wearer and attached to the said side edge at points comparatively close to the transverse center line of the veil.

In testimony whereof I have signed my name to this specification in the presence of two witnesses.

BLANCHE MARGARITA STRACHAN.

Witnesses:
